(57) **CLAIM**

The ornamental design for an plug-in angled outlet cover, as shown and described.

DESCRIPTION

FIG. 1 is a perspective view of an plug-in angled outlet cover showing my design;

FIG. 2 is a front view of the plug-in angled outlet cover of FIG. 1;

FIG. 3 is a left side elevational view of the plug-in angled outlet cover of FIG. 1 (right side is mirror image);

FIG. 4 is a top view of the plug-in angled outlet cover of FIG. 1;

FIG. 5 is a bottom view of the plug-in angled outlet cover of FIG. 1;

FIG. 6 is rear view of the plug-in angled outlet cover of FIG. 1

FIG. 7 is a perspective view of an plug-in angled outlet cover showing an alternative embodiment of my design;

FIG. 8 is a front view of the plug-in angled outlet cover of FIG. 7;

FIG. 9 is a left side elevational view of the plug-in angled outlet cover of FIG. 7 (right side is mirror image);

FIG. 10 is a top view of the plug-in angled outlet cover of FIG. 7;

FIG. 11 is a bottom view of the plug-in angled outlet cover of FIG. 7; and,

FIG. 12 is rear view of the plug-in angled outlet cover of FIG. 7.

The broken lines are for environmental purposes only and form no part of the claimed design.
